UNITED STATES PATENT OFFICE.

ALBERT H. YODER, OF WILBURTON, AND EDWARD HAGERTY, OF CENTRALIA, PENNSYLVANIA, ASSIGNORS OF ONE-HALF TO ELMER E. STRAUB, OF WILBURTON, PENNSYLVANIA.

SEGMENT FOR SIZING-SCREENS.

1,279,630.

Specification of Letters Patent.

Patented Sept. 24, 1918.

Application filed February 24, 1917. Serial No. 150,751.

To all whom it may concern:

Be it known that we, ALBERT H. YODER and EDWARD HAGERTY, citizens of the United States, residing respectively, at Wilburton and Centralia, in the county of Columbia, and State of Pennsylvania, have invented new and useful Segments for Sizing-Screens, of which the following is a specification.

The present invention appertains to shaking screens, such as used for sizing anthracite coal or other material, and aims to provide a novel and improved joint for the segments or sections of the screen.

The segments, according to the prevailing practice, are ordinarily overlapped at their meeting edges, and the overlapped edges are apertured for the reception of bolts, which clamp the overlapped edges together. This requires the use of a comparatively large number of bolts, and even then, the joints between the segments are more or less weak and inefficient, the bolts or securing elements breaking and wearing out due to the conditions to which they are subjected, and the portions of the segments between the bolts sagged or bending thereby permitting of the intermingling of the different sizes of material, which is objectionable. The ordinary lap joints are also objectionable, in that they require considerable time and labor in assembling and separating the segments.

It is the object of this invention to provide novel means for assembling the segments or sections of the screen, which will eliminate the objections resulting from the use of the ordinary lap joints, no bolts or securing elements being necessary to secure the segments together, but the joints are nevertheless stronger in construction without requiring any appreciable increase in the amount of material used. The present joint enables the segments to be readily assembled and separated for purpose of repair or replacement, thereby saving time and labor, and the intermingling of the various sizes of materials being screened is avoided due to the fact that the materials cannot work through the joints of the segments. The sagging of the joints is also overcome, due to the stiffening of the joints by reason of the present improvements, and there are no bolt heads or other parts to be knocked or worn off by the movement of the material over the joints.

It is also the object of the invention to

provide the foregoing improvements which are extremely simple and inexpensive to incorporate in the sizing screens.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:—

Figure 1 is a perspective view of a fragmental portion of a sizing screen, and illustrating the present improvements, portions being broken away.

Fig. 2 is a section on the line 2—2 of Fig. 1.

Fig. 3 is a view similar to Fig. 2 illustrating a modification.

In carrying out the invention, the segments or sections 1 which are in the form of apertured plates, are provided, as usual, at their side edges with upturned flanges 2 provided with apertures or slots 3 for bolting them to the side supports. In order to secure the companion segments together, one edge of one segment is provided with a flange or lip 4 bent upwardly at substantially right angles between the respective ends of the flanges 2, the flange 4 being of less height than the flanges 2. The corresponding edge 5 of the companion segment projects slightly beyond the ends of the respective flanges 2 over the edge of the flange 4, and the edge 5 is provided with a depending flange or lip 6 bent downwardly at substantially right angles and overlapping the flange 4, whereby to provide a lap joint at substantially right angles to the planes of the segments. The ends of the flanges 2 of the segments can be in abutment with the edge portion 5 of one segment projecting between the flanges 2 of the other segment. The flanges or lips 4 and 6 being bent at an angle from the segment will stiffen the joints, whereby to prevent the sagging thereof, and no bolts or securing elements are necessary to clamp the overlapping portions together, nor is it possible for the material to work through the joint. The joint

is used between each pair of segments or sections, one edge of each segment having the upturned flange 4 and the other edge having the down-turned flange 6. The 5 flanges 4 are preferably at the upper ends of the segments, if they are slightly inclined, while the flanges 6 are at the lower edges.

Fig. 3 illustrates a variation in the joint. One segment has the upturned flange 4' 10 which is bent into hook form to provide the lip 4" overhanging the segment. The edge portion 5' of the other segment which extends between the flanges 2 of the first mentioned segment rests upon the lip 4" and is 15 provided with a depending or downturned flange 6' abutting the edge of the lip 4" and bent back into hook form to interengage with the hook-shaped edge of the first mentioned section and providing the lip 6" to 20 underlie the lip 4". This will provide even a more secure joint for the segment.

In assembling the device shown in Fig. 3, the side flanges of the upper segment are placed between the side flanges of the lower segment, the side flanges of the upper segment springing inwardly, and the side flanges of the lower segment springing outwardly. This spring movement is very slight for several reasons, and works no permanent damage to the device. It is slight 25 because, as shown in Fig. 3, the bottom of the upper segment is elevated above the bottom of the lower segment, and consequently, the amount that the side flanges of the lower segment are sprung outwardly is much less than would be the case if the bottom of the upper segment rested directly on the bottom of the lower segment. Most of the 30 springing takes place in the side flanges of the lower segment, but the side flanges of the upper segment may spring inwardly to some extent, the springing thus being divided to some degree at least between the flanges of the upper and lower segments. Since the 35 flanges of the segments are supplied near to their ends with the slots 3, the resiliency of the flanges is enhanced to some extent. If the segments are pulled in opposite directions, the parts 4" and 6" will interlock, as 40 shown in Fig. 3, the side flanges of one seg- 45

ment springing back into alignment with the side flanges of the other segment. The operation above described may be carried out readily and the parts will coact with sufficient exactness to satisfy the requirements imposed on a coal screen, it being recalled that, in a device of the class described, a micrometric coöperation between coacting parts is not necessary. 55

Having thus described the invention, what is claimed as new is:—

1. A screen embodying segments having upturned side flanges, one segment provided at one edge between its side flanges with a portion extending upwardly at an angle to 60 stiffen the segment and having an overhanging lip forming a hook, and the other segment having its adjacent edge lip and provided with a portion extending downwardly at an angle to stiffen said edge portion and having a lip underlying the aforesaid lip to form a hook interengaged with the aforesaid hook. 70

2. A screen embodying segments having upturned side flanges, one segment provided at one edge between its side flanges with a portion extending upwardly at an angle to 75 stiffen and support said edge without the aid of other means, and the other segment having its adjacent edge portion extending over said portion between the side flanges of the first mentioned segment and provided with a portion extending downwardly at an angle to stiffen and support said edge portion without the aid of other means and overlap the aforesaid portion to prevent the material passing between them, and to hold the segments against separation without the aid of other means, the ends of the side flanges of the two segments abutting to hold said 80 portions in overlapped relation and prevent their separation. 85

In testimony that we claim the foregoing as our own, we have hereto affixed our signatures in the presence of two witnesses.

ALBERT H. YODER.
EDWARD HAGERTY.
